UNITED STATES PATENT OFFICE.

ARTHUR W. COX, OF BALLARD VALE, MASSACHUSETTS.

DESIGN FOR A COMBINED KNIFE AND FORK.

SPECIFICATION forming part of Design No. 18,776, dated December 4, 1888.

Application filed October 27, 1888. Serial No. 289,343. Term of patent 3½ years.

To all whom it may concern:

Be it known that I, ARTHUR W. COX, a citizen of the United States, residing at Ballard Vale, in the county of Essex and State of Massachusetts, have invented and produced a new and original Design for a Combined Knife and Fork; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to a novel design for a combined knife and fork, which will be hereinafter more fully described, and shown in the accompanying drawings, in which—

20 Figure 1 is a side view of a combined knife and fork embodying my invention; Fig. 2, an edge view of the device, and Fig. 3 a section on the line $x x$ of Fig. 1.

25 The leading feature of the design consists in the general form and outline of the article, and particularly in the contour of the fork,

the prongs of which curve downwardly in the direction of their length, the sides of the lower prong converging to a knife-edge.

The handle A and the fork B are in the same straight plane, the handle contracting 30 at a and expanding laterally and vertically at b . The fork B, contracted at D, curves downwardly between its end and the contracted portion D, or, in other words, is curved in the direction of its length. The lower prong, C, 35 is beveled to a knife-edge, and the upper edge of the fork is provided with the vertical extension E, close to the vertical and laterally-expanded portion b .

Having thus described my invention, what I 40 claim, and desire to secure by Letters Patent, is—

The design for a combined knife and fork, substantially as herein shown and described.

45 In testimony whereof I affix my signature in presence of two witnesses.

ARTHUR W. COX.

Witnesses:

HOWARD GANNETT,
GEORGE T. CURRIER.
